[57] **CLAIM**

The ornamental design for a measuring receptacle with a slidably removable bottom, substantially as shown and described.

DESCRIPTION

FIG. 1 is a perspective view of a measuring receptacle with slidably removable bottom showing my new design;

FIG. 2 is a top plan view thereof;

FIG. 3 is a side elevational view thereof;

FIG. 4 is a side elevational view thereof taken in the direction opposite to that of FIG. 3;

FIG. 5 is an end view thereof.

The bottom face of the removable bottom is planar.

Fig. 1.

Fig. 2.

Fig. 3.

Fig. 4.

Fig. 5.
